US00D856942S

(12) **United States Design Patent** (10) Patent No.: **US D856,942 S**
 Chen et al. (45) Date of Patent: **** Aug. 20, 2019**

(54) **SMART SPRINKLER CONTROLLER**

(71) Applicant: **HANGZHOU LIANLUO
INTERACTIVE INFORMATION
TECHNOLOGY CO., LTD.,**
Hangzhou, Zhejiang (CN)

(72) Inventors: **Li Chen**, Hangzhou (CN); **Hanmu Qi**, Hangzhou (CN); **Daodong Zhang**, Hangzhou (CN); **Shaolu Liu**, Hangzhou (CN); **Hongjing Wang**, Hangzhou (CN)

(73) Assignee: **HANGZHOU LIANLUO
INTERACTIVE INFORMATION
TECHNOLOGY CO., LTD.,**
Hangzhou, Zhejiang (CN)

(**) Term: **15 Years**

(21) Appl. No.: **29/635,806**

(22) Filed: **Feb. 2, 2018**

(30) **Foreign Application Priority Data**

Dec. 12, 2017 (CN) 2017 3 0629599

(51) LOC (12) Cl. **14-03**

(52) U.S. Cl.

USPC **D13/168**

(58) **Field of Classification Search**

USPC D13/162, 168, 184; D14/125, 218, 240,
D14/242, 358

CPC A01G 25/16; A01G 25/165; A01G 25/167;
A01G 27/003; G05B 15/02; G05B 19/02;

Primary Examiner — Selina Sikder

(74) Attorney, Agent, or Firm — Baker & Hostetler LLP

(57) **CLAIM**

We claim the ornamental design for smart sprinkler controller, as shown and described.

DESCRIPTION

FIG. 1 is the front view for smart sprinkler controller, showing my new design.

FIG. 2 is the rear view for smart sprinkler controller, showing my new design.

FIG. 3 is the left-side view for smart sprinkler controller, showing my new design.

FIG. 4 is the right-side view for smart sprinkler controller, showing my new design.

FIG. 5 is the top view for smart sprinkler controller, showing my new design.

FIG. 6 is the bottom view for smart sprinkler controller, showing my new design; and,

FIG. 7 is the perspective view for smart sprinkler controller, showing my new design.

1 Claim, 5 Drawing Sheets
